METHOD AND APPARATUS FOR COATING

Charles W. Abbott, Larchmont, N. Y.

Application October 12, 1940, Serial No. 360,914

27 Claims.

5 This invention relates to a method and apparatus for applying a coating material to a moving element, such as an insulated electrical conductor.

10 One of the objects of this invention is to provide a simple, practical, and efficient method and apparatus for applying a coating material to an elongated element of which the insulating jacket of an electrical conductor may be considered an illustration. Another object is to provide a method and apparatus of the above-mentioned character that will be well adapted to meet the hard conditions of high speed and quantity production. Another object is to provide a method for applying the coating material to an elongated element that can be carried on efficiently and inexpensively under the conditions of or in association with existing methods of manufacture of the elongated element itself and with convenience and facility and with little if any interference with or interruption of such existing methods of manufacture. Another object is to provide an apparatus for applying a coating material that will be of dependable and adequate continuity of action to permit it to be safely associated with existing apparatus or methods of manufacture of such elements without jeopardizing the production performance of the latter.

Another object is to provide a coating applicator capable of long service. Another object is to provide a simple and dependable control of application of coating material to an element of the above-mentioned character. Another object is to provide a method and apparatus for dependably controlling the application of a coating material to a moving elongated element, to suit the application to varying conditions of speed of movement of the element, length of "run" of the latter, and like conditions or requirements met with in practice. Another object is to provide an applicator apparatus of the above-mentioned character that will be capable in a simple, inexpensive and efficient way of overcoming the difficulties and disadvantages that flow from wear of certain parts.

Another object is to provide a multiple-applicator structure with simple, dependable and easily operated or controlled means for making effective upon the element to be coated an additional applicator or applicators. Another object is to provide, in a method and apparatus for applying a coating material to a moving elongated element, simple, practical and efficient means for replacing a worn applicator device.

Another object is to provide a method and ap-

paratus for applying a coating material to an elongated element that will function dependably under conditions of substantial speed of movement of the element and substantial length of run thereof. Another object is in general to provide an improved method and apparatus for applying a coating material and other objects will be in part obvious or in part pointed out hereinafter.

15 The invention accordingly consists in the features of construction, combinations of elements, arrangements of parts, and in the several steps and relation and order of each of the same to one or more of the others, all as will be illustratively described herein, and the scope of the application of which will be indicated in the following claims.

20 In the accompanying drawings in which is shown a preferred embodiment of the mechanical features of my invention,

Figure 1 is a plan or top view of a coating-applicator apparatus, certain parts being broken away;

25 Figure 2 is a longitudinal central sectional view, as seen along the line 2-2 of Figure 1, certain parts being broken away;

Figure 3 is an end elevation as seen from the left in Figure 1;

30 Figure 4 is an end elevation, as seen from the right of Figure 1;

Figure 5 is an elevation as seen along the line 5-5 of Figure 2;

35 Figure 6 is a longitudinal central sectional view, certain parts being shown in elevation, like that of Figure 2, showing another form of apparatus; and

Figure 7 is an end elevation as seen from the right in Figure 6.

Similar reference characters refer to similar parts throughout the several views of the drawings.

40 As conducive to a clearer understanding of certain features of my invention, it might at this point be noted that, where it is desired to apply coating material to an elongated element, conditions of manufacture of the latter frequently require movement of the element in substantial lengths or runs and at substantial rates of speed, and that, while applicator devices or methods 45 as heretofore proposed succeed in applying a coating, they are dependable only throughout relatively short lengths or short portions of a production run and hence cause interruption in production and other disadvantages. For example, 50 as a rubber or like applicator element, initially

suited to apply a coating of the desired material at the desired thickness, is subjected to wear, causing change in rate or thickness of coating application; where the element is produced at a high rate of lineal footage per time interval, as, for example, in the manufacture of rubber jacketed electrical conductor, such as so-called lamp cord, as by the process of continuous vulcanization of the rubber as and after it leaves the extrusion head, such wear, if the application is made as the vulcanized rubber element moves along, may be in point of time rapid even though considerable footage of the element has passed therethrough. Where the application is of a heat-responsive coating material, that is, one that is set by heat, and the application proceeds after emergence of the element from the continuous vulcanizing step or apparatus so as to utilize the heat content of the element, the effect of the resultant operating temperatures upon the applicator device may contribute to its alteration, wear or deterioration. Other factors, like the cross-sections involved, ingredients of the coating material, etc., may also contribute to such effects. Thus, speeds on the order of several hundred feet per minute and temperature conditions of several hundred degrees F. may contribute to wear or other detrimental change in the applicator device with such results that, though a substantial length of element is suitably coated, by the time wear or change has taken place that length of element may be only a portion of the total length or run which the method or apparatus of manufacture of the element is intended or should produce without material interruption. Thus, in manufacture of lamp cord a single unbroken, uninterrupted run may be made at a rate of 250 to 300 feet per minute and usually totals 60,000 or 70,000 feet. In general, the higher the speed of movement of the element, the greater and more rapid is the wear on the applicator device. One of the dominant aims of this invention is to provide a method and apparatus that will dependably effect coating of an element under conditions of manufacture of the latter, such as those mentioned above and without detrimentally affecting the efficiency or economy of such methods or apparatus of manufacture, and in general to avoid in a simple, inexpensive and practical way such disadvantages of prior devices as those mentioned above.

For purposes of illustration but not by way of limitation, the element selected to illustrate the method and apparatus of my invention and indicated by the reference character 10 is a rubber jacketed conductor of the so-called lamp cord type having illustratively two conductors 11, 12 (Figure 4) jacketed and insulated by the rubber element 10, being usually of an elongated cross-section approximating an oval, and, for purposes of further illustration, let it be assumed that the conductor 10, moving into the applicator construction shown in Figures 1 and 2 in a direction from the left to the right, has just left the continuous vulcanizing apparatus usually associated directly with the extrusion head by which the compound, such as rubber, is extruded onto the two conductors. The continuous vulcanizer may be of any suitable construction and usually comprises a long pipe-like chamber having therein a suitable heating medium, such as steam, and being of sufficient length so that, with respect to the character of the compound and the temperature maintained by the heating medium, the extruded compound emerges from the chamber substan-

tially vulcanized, now being the element 10. Its rate of movement is on the order of the speeds mentioned above and its temperature may be several hundred degrees F. Suitable means, such as a suitably driven capstan, preferably coacting with suitable guiding means, such as rollers (not shown in the drawings), are employed to maintain the desired speed of movement and to maintain the element at a suitable tautness along a line or axis of movement appropriately aligned with respect to the continuous vulcanizer. It is intermediate of the latter and of the capstan that I prefer to apply the coating, particularly where, as is preferred, the coating material is of the above-mentioned heat-responsive type.

Accordingly, I secure or mount by any suitable means a suitable support or bracket 13 transversely of the path of travel of the element 10 and intermediate of the continuous vulcanizer and the capstan. Bracket 13 may be in the form of an upstanding plate-like member and where it intersects the path of travel of element 10 it is provided with a suitable hole 14 for the passage therethrough of the element 10. Preferably at the entry side of the bracket 13 I provide suitable guiding means for the moving element 10 to aid in steadyng the latter against vibration or whipping.

Such guiding means may take any suitable form, preferably and illustratively comprising two guide rollers or sheaves 15, 16 suitably grooved to complement each other relative to the cross-section of the element 13 as appears better from Figures 3 and 1.

Preferably guide rollers 15, 16 are relatively shiftable to facilitate bringing them into or out of operative relation to the element 10 and preferably both are shiftable and normally urged yieldably one toward the other.

Thus, for example, the guide rollers may be supported in a mounting plate 17 secured in any suitable way as by rivets 18 to the bracket 13 and relative to which the rollers are shiftable. Thus, mounting plate 17 may be provided with two L-shaped grooves 20, 21 through which are secured to or forming part of cylindrical cup-like supports 24, 25, respectively, into which are pressed the outer races of suitable antifriction bearings 26, 27 whose inner races have secured to them stud-like extensions of the rollers 15 and 16, whereby the latter are supported for rotation relative to their cup-like supports 24, 25.

Suitable means, such as disk-like elements 28, 29, are secured to the studs 22, 23, respectively, to coact with the cup-like supports of the latter in holding them against movement out of the L-shaped slots while allowing sufficient clearance to permit sliding of the mountings and their respective guide rollers along their respective guide slots in the mounting plate 17. Suitable means are provided to urge each roller in a direction toward the element 10 which it is to aid in guiding, and conveniently a spring 30 (Figure 3) having its ends engaging the studs 22, 23 is under sufficient tension to achieve this effect, when the studs 22, 23 are in the aligned portions of the L-shaped slots 20, 21, as shown in Figure 1. With such an arrangement as this, also, either or both of the guide rollers may be moved away from the path of the element 10 and to an out-of-the-way position, as by shifting its stud along that portion of the slot that is transverse to the path of travel of element 10 and into the other portion that is substantially parallel to the ele-

ment 10, spring 30 yielding for that purpose. And when both studs are so moved into the ends of the parallel portions of the slots, the spring 30 aids in holding them and their associated guide rollers in the resultant position where the rollers are displaced one from the other. To facilitate such manual control of the guide rollers, suitable handles 31, 32 may be employed. For example, they may comprise upward extensions of the stud shafts of the respective guide rollers 15 and 16.

With such means as the rollers 15, 16, the moving element 10 may be steadied and where it is of a cross-section other than circular the element 10 may thus also be held, during its movement, against twisting, particularly where, as in the illustrative embodiment, the applicator device has active portions cross-sectioned substantially to match the illustrative oval cross-section of the element 10. To the right of the guide means 15—16 I provide suitable means for supplying to the moving element 10 a suitable quantity of the coating material which may be of any suitable character or composition, preferably at this stage being in liquid form. Where the coating material is to be responsive to the heat content of the element 10 and/or the conductor within the latter, various coating materials or compounds may be employed and, for purposes of illustration, let it be assumed that the material is a lacquer, such as a lacquer made up of nitrocellulose and a suitable plasticiser, with suitable solvents. In the latter case, a suitable means may comprise a chamber 34 generally cylindrical and preferably tapered at its lower end into nozzle-like shape where it is provided with an aperture 35, the member 34 being mounted, preferably in the manner hereinafter described, at the upper portion of the supporting bracket 13, being thereby positioned so that its discharge aperture 35 (see Figures 1, 2 and 3) is above the element 10 and in line with its axis or center line.

The upper end of the chamber structure 34 is provided with a pipe-like extension 37 to which a suitable pipe or tube may be attached or connected and by which the coating material in liquid form is supplied to the chamber 34, preferably under suitable pressure.

The size of the discharge aperture 35 and the pressure of the supply of coating material are suitably related to each other and to such factors as the composition of the coating material, the speed of movement of the element 10, the external area of the latter, and the like, so that the rate of supply of coating material to the moving element 10 is sufficient to discharge upon the upper surface of element 10 the desired amount of covering material to provide the desired thickness of coating when appropriately spread thereover.

Preferably, also, the discharge chamber 34 is provided with suitable means for clearing the aperture 35 and preferably also for closing it as desired. A convenient and preferred means comprises a plunger 38 suitably mounted for up and down movement with the chamber 34, as, for example, by providing the cap-like closure 40 of the chamber 34 with a suitable aperture through which the plunger 38 passes movably, suitable means (not shown) being provided to maintain the sliding connection or joint sealed, if desired.

At its lower end plunger 38 carries or is shaped to provide a needle point 41 which by the

mounting of plunger 38 is aligned with the aperture 35. Accordingly, should the aperture 35 become clogged plunger 38 may be moved downwardly to move needle point 41 through the aperture 35 and thus clear it. To close off the aperture 35 plunger 38 may be moved downwardly and held with needle point 41 within and closing off the aperture 35. Also, if desired, and by suitably proportioning the size and shape of the aperture 35 and needle point 41, a control of the rate of discharge of coating material, as by a throttling action, may be had by varying the relationship between the needle point and the walls of the aperture. Also, as is indicated in Figure 1, a suitable chuck may be provided for removably mounting the needle point 41 to the lower end of the plunger 38.

I preferably provide suitable means for facilitating the control of needle point 41. Thus, its upper external end may be provided with a handle 42 for manipulating it and illustratively an upper shank portion of the plunger 38 may be threaded, as at 38a, and thus placed in threaded connection with a threaded hole in the cap member 41, so that turning of the plunger 38 by handle 42 effects raising or lowering movement; a spring 43 preferably surrounding the upper end of plunger 38 and interposed between the handle 42 and the cap closure 40 may serve to hold the plunger normally against rotation.

With coating material supplied to the element 10, the material is distributed or spread about the external surface of the element 10 by the coaction with the moving element 10 of an applicator element or elements of which one applicator element, indicated at 47 in Figure 2, is shown in such coacting relationship, taking the form, illustratively and preferably, of a nipple-like member of suitable yieldable material and having an aperture through which the element 10 moves, the aperture having preferably a configuration substantially matching the shape of the element 10 and being in any suitable way dimensioned or conformed to act as a sort of wiper to spread the coating material carried by the element 10 about its external surface and in a layer of the desired thickness.

The applicator element, such as element 47, may be made of any suitable material and preferably is made of a rubber or like substance. It thus preferably has a suitable degree of pliancy and resiliency, particularly in the region of its aperture or mouth-like portion which, in relation to the speed of movement of element 10 and the rate of supply of coating material to the moving element 10, determines the thickness of the layer of coating material with which the element 10 leaves the device and continues to move toward the right. Though the coating material may function somewhat as a lubricant or protecting element to shield the wiping portions of the applicator against the friction and wear resulting from the relative movement, the material employed is preferably also tough in order thus better to stand up against such friction and wear as actually take place.

The discharge device 34, set to discharge coating material onto the moving element 10 at an appropriate rate, as above indicated, has, among its various advantages, the avoidance of appreciable or material change in density or viscosity of the coating material where the latter is applied to the element 10 with the latter in heated condition; even though element 10 is at a substantial temperature and even though the de-

vice 34 supplies coating material to it at a steady rate, the applied coating material is steadily and speedily moved into coaction with the active applicator element 47 so that as the process continues the applicator element 47 operates upon coating material of consistently substantially constant viscosity or consistency, thus contributing toward achieving uniformity of spreading action. Were the element 10 to be drawn through a chamber or vessel that contains the coating material, the heat content in the element 10 would tend to progressively raise the temperature of the quantity of coating material through which it is drawn and thus would have the effect of progressively driving off volatile or like constituents and hence would change the consistency of the coating material and correspondingly alter the wiping or spreading action of the applicator element 47.

Where the moving element to be coated is also at a temperature above normal operating or room temperatures as, for example, where the coating is applied shortly after or partially coincident with the step of vulcanization or where the element 10 is otherwise provided with a heat content to coact with an applied heat-responsive coating material, the material of the applicator element, like member 47, is preferably also resistant to heat effects. Thus, heat-resistant rubbers may be employed, such as a material known under the trade name "Thiocal." Also, various synthetics may be employed, such as a material known by the trade name "Neoprene."

In the illustrative embodiment, applicator element 47 may comprise an end wall 47^a generally circular in shape having at its center an aperture suitably shaped with respect to the shape of the cross-section of element 10 and preferably is conformed as at 47^b, about this aperture, to provide a continuous lip which may yieldably and preferably resiliently lay itself against and about the moving element 10, somewhat as indicated in Figure 2, with sufficient pressure and sufficient surface of contact to insure the desired wiping and spreading or distributing action. A suitable degree of yieldability or flexibility may here be achieved by the inherent qualities of the material employed or by varying the thickness of the material, as by tapering it in cross-section, or the like.

Such or other suitable means may be employed to give the applicator device 47 the characteristics desired for achieving the intended thickness of coating and for achieving as great durability or life as is possible. Nevertheless, and as earlier above indicated, and particularly at high speeds of movement of the element to be coated, the life of the active parts of the applicator device may be long or substantial when measured in footage of element coated but is comparatively short when measured in relation to elapsed time or when measured in relation to the total or over-all footage of a single production run in the making of element 10 itself. The end of the effective life of the applicator device is indicated by change in the coating applied, usually by non-uniformity of thickness or by more or less non-uniformity of distribution or of application of the coating material to the element. When this occurs or at such time interval when it is about to occur, I make provision for quickly and speedily bringing another applicator device into action upon the element 10, preferably in substitution of the one whose effective life has come or is about to come to an end or whose effective or desired action has

ceased, and an illustrative and preferred arrangement and construction are like that shown in Figure 2 where, it will be noted, a number of applicator elements or devices, illustratively thirteen, as suggested in Figure 2, are mounted and arranged with their apertures or lip portions coaxial and arranged in effect in series.

In carrying out the just stated arrangement, I may provide each applicator device 47 with a cylindrical wall portion 47^c stepped or flanged as at 47^d, the parts being so proportioned that the cylinder flange 47^d of one applicator element takes over the side wall portion 47^c of the next or adjacent applicator element, and preferably these overlapping portions of successive applicator elements are secured together preferably in a manner to facilitate relative ease of detaching one from the other. Thus, the applicator elements arranged in the series may at these contacting or overlapping portions be cemented together by a cement which, while adequately secure to maintain the assembly of the elements, gives way under appropriate manual or like manipulation to effect separation of the two cemented parts. Or, where the applicators are made of rubber, they may be vulcanized together at their junction or overlap or cemented.

All of the devices 47 are preferably of identical configuration so as to facilitate manufacture in quantities and to give wide range of selection of the number to be made up in any one composite unit, excepting that the endmost applicator element, the one at the left in Figure 2, may be constructed to provide also a mounting means for itself and the rest of the elements secured to it. Thus, the cylindrical wall portion 47^c of this innermost element may have a sleeve-like extension 47^e, reinforced, if desired, by an end portion or flange 47^f of greater thickness, so that it may be expanded or stretched over and onto a support 50 which preferably takes the form of a metallic sleeve carried by or secured to a carrier plate 51 suitably supported or carried by the bracket 13, preferably in the illustrative manner later described, so as to hold the sleeve 50 and hence the supporting portions 47^c-47^a of the assembly coaxially with the moving element 10.

Extending toward the right, as viewed in Figures 1 and 2, from the bracket 13 and preferably from the hole 14 therein, is a member 52, preferably tubular, and preferably supported from the bracket 13 in a position to be coaxial with the line or path of movement of the element 10. Internally the tubular member 52 is large enough to leave substantial clearance between its inside walls and the outside surface of the moving element 10 and the coating material carried by the latter and conveniently it is of uniform wall thickness and preferably presents a shape of cross-section geometrically similar, or substantially so, to the external cross-section of the element 10 and hence also to the shape of the mouth or aperture of each of the applicator elements 47. In length, the tubular element 52 is sufficient to extend through the mouths or lipped operating portions of all of the applicator elements excepting the endmost one, that is, the one at the extreme right, as seen in Figure 2. And hence, when the multiple applicator unit is assemblable to its support 50, as by sleeving it onto and over the tubular member 52, the latter expands the apertures or mouths of all of the applicator elements excepting the above-mentioned

endmost one, the material of the elements being, as above pointed out, resilient or elastic. Each of the applicator elements is thus held out of operative relation to the moving element 10 and is in effect screened off by the tubular member 52 and each thus finds some mechanical support from the member 52, the latter functioning in the illustrative embodiment by a cantilever action due to its fastening at one end, as later described, to the bracket 13. The endmost applicator, however, is unrestricted by the tube member 52 and hence its aperture or mouth portion is exposed into operative relation to the moving element 10 and the latter, upon commencing the operation, is threaded through that exposed endmost applicator element which, by the mechanical actions above-mentioned, is supported coaxially with the moving element 10.

The tubular member 52 may be constructed of any suitable material but where the moving element 10 has substantial tendency to vibrate or whip I prefer that the applicator element that happens to be operative upon the moving element 10 at the right-hand end of the tubular member 52 be permitted to partake of some motion of translation in directions transverse to the axis of the moving element 10, so that it may more or less follow or respond to vibration or sidesway or whipping of the moving element 10 itself. For this purpose I prefer to construct tubular member 52 to be flexible in sufficient degree to permit the just-mentioned action to take place. Thus, I may build the tubular member 52 up by winding wire of suitable characteristics, such as piano wire, preferably of small diameter, into a helix to form a core and interweave or interrelate therewith threads of cotton or like material, preferably utilizing a suitable saturant and finish for the latter, such as a phenolic resin, which is flexible and preferably also impervious to ingredients of the coating material and also capable of standing the imposed ambient temperature (where the element 10 is run through in heated condition), thus giving it characteristics which the applicator elements themselves preferably also have as above pointed out. With such a construction, dependable expansion of the mouths of the inactive applicator elements may be had and also satisfactory mechanical support for the latter, while the tube member 52 has sufficient bendability or yieldability to permit its right-hand end and hence the active applicator element or elements to follow or respond to transverse displacement of the moving element 10 itself.

When the time interval of the life of the exposed and active applicator element or elements has elapsed or when by any other means of determination or for any other reason it is desired to bring into action a new applicator device, the multiple applicator assembly, including the mounting plate 51, is shifted toward the right, as viewed in Figure 2, by a distance equal to the equal spacing between the serially arranged applicator devices, thus, in effect, withdrawing the supporting and expander tube member 52 from the next succeeding applicator element or device which contracts onto and about the still moving element 10 and takes over the action of controlling and determining the thickness and distribution of the coating material onto the element 10. This step is repeated preferably at periodic intervals until the over-all footage of the single continuous run of production of the

element 10 is completed, whence the entire apparatus, including the extrusion and vulcanizing means are halted for preparation for the next run. Thus, I am enabled to insure avoidance of interruption of the continuity of production of each run, the multiple applicator assembly comprising enough applicator elements, including a suitable factor of safety, to insure that the entire run can be achieved without interruption. Depending upon the footage of a single run and the speed of movement of the element 10 and related factors, the number of applicator devices successively made effective will, of course, vary.

Preferably, I provide suitable means for achieving the desired step-by-step progression of applicator devices into operative relation to the moving element. For example, I may support the supporting plate 51 movably with respect to the bracket 13 and preferably in a manner to insure that such step-by-step progressive movement is effected, and illustratively I may utilize a suitable number, illustratively two, supporting bars 53, 54, preferably arranged in parallelism to each other and secured to the bracket 13, being of a length commensurate with the length of the tubular member 52; such longitudinally extending supports I may provide with slots or notches 55 having the same spacing as the spacing between the successive applicator elements of the multiple unit.

The slots 55 are preferably of a width to receive relatively snugly the thickness of the mounting plate which is preferably apertured at its upper and lower ends, as at 57 and 58, to receive therethrough the supporting bars 53 and 54, respectively. The coating parts are preferably so proportioned or shaped, as by giving the slots 55 a sufficient depth so that the remaining metal can be rounded off into substantially cylindrical form of a diameter about equal to the narrower dimension of the elongated slots 57, 58 in the mounting plate 51, thus permitting the supporting bars to be given a rotary movement when the mounting plate 51 is engaged in or aligned with companion slots 55 of the two supporting bars 53, 54.

For this purpose, also, I prefer to support the supporting bars 53, 54 from the supporting bracket 13 preferably in a way to facilitate rotational movement of the bars about the respective axes of the above-mentioned cylindrical portions at the bases of the slots 55. Thus, each of the two bars 53, 54 may have an extension 59 preferably cylindrical and aligned with the cylindrical portions at the bases of the slots and extending through suitable bearing holes in the bracket 13, suitable means being provided for holding the bars against longitudinal displacement relative to the bracket 13 and preferably also suitable means for yieldingly holding the bars in whatever position may be given them by rotary movement. A convenient and illustrative means for these purposes may comprise spring washers 60 interposed between the left-hand face of the supporting bracket structure and, for example, nuts 61 threaded onto the extreme ends of the bar extension 59, any suitable means, such as a collar 62, fixed to the inner portions of the bar extension 59 being provided to bear against the opposite face of the supporting bracket structure, thus to coact with the spring washers 60 and nuts 61 in holding the supporting bars 53, 54 parallel to each other and with their respective slots 55 transversely aligned.

Supporting bars 53, 54 are equidistantly spaced from the axis of the tubular element 52 and the elongated slots 57 and 58 (Figure 4) in the mounting plate 51 are so positioned, being also equidistantly spaced from the axis of the mounting collar 50, that the respective cylindrical portions at the bases of any two transversely aligned slots 55, 55 bottom respectively in the upper and lower ends of the slots 57 and 58. Accordingly, when the bars 53 and 54 are rotated to a position to face their respective slots 55 toward each other, bar 53 is in alignment with the slot 57 and bar 54 is in alignment with the slot 58, whence mounting plate 51, with a multiple nipple or applicator assembly attached to its collar 50, may be slipped onto the free ends of the bars 53, 54 and moved to a position substantially in alignment with that pair of transversely paired or aligned slots 55, 55 which is nearest the bracket 53, all of the applicator elements being expanded onto and over the tubular member 52 excepting the one at the extreme right-hand end of the multiple assembly; thence the two bars 53, 54 may be by hand or by the use of a simple implement given a rotary movement throughout a sufficient angle to relate this pair of slots to the mounting plate 51 in a manner to set the latter in the slots, as shown in Figure 2, whence mounting plate 51 and the multiple applicator assembly are held fixedly against displacement and in proper alignment and relationship to the other parts.

As soon as it becomes necessary to bring another applicator element into action, and this may be determined in various ways, as indicated above, the two bars 53, 54 are given a rotary movement in retrograde direction, thus bringing them into alignment with the respective elongated slots 57 and 58 in the mounting plate 51, whence the assemblage with the mounting plate 51 may be moved as a unit toward the right, being guided by the spaced supporting bars 53, 54, by a distance equal to the spacing between successive slots 55, thus bringing the mounting plate 51 into alignment with the next succeeding pair of slots 55, 55, such movement being effected to slide all of the expanded applicator elements along the tubular member 52 by a corresponding distance, bringing one of them out of engagement with the right-hand end of tubular member 52 and thus permitting it to snap onto or contract about the moving element 10 and undertake immediately the task of evenly spreading and applying the coating material to element 10. The parts may again be locked in this new position, as by giving the bars 53, 54 a sufficient rotary movement to ride the slots 55, 55 into locking relation to the mounting plate 51. Such steps as these may be repeated, without interrupting the continuity or speed of motion of the element 10, at suitable intervals, as indicated above, and thus application of coating material may proceed without interrupting a "run" of production of element 10.

An arrangement like that just described also has flexibility as to control or mode of operation. For example, I may leave both supporting bars 53 and 54 in such positions that, in cross-section or as viewed in Figure 4, they are in general alignment with the elongated slots in the mounting plate 51 and with their respective slots 55 exposed upwardly. In such case, to effect a shift of the mounting plate 51 with its multiple applicator unit, mounting plate 51 need be simply raised to disengage it from two companion

slots in the supporting bars 53 and 54, then shifted and let down into the next succeeding pair of transversely aligned slots 55; for such mode of operation, the cylindrical portions of the two supporting bars normally bottom in the upper ends of the elongated slots in the mounting plate 51. In operating the mechanism in this manner, rotational movement of the two supporting bars need not be resorted to, though one or both may be given a slight rotary movement thus in effect to lock the mounting plate 51 against unintentional displacement.

Or, I may effect, by suitable power means, an advancing movement of the multiple applicator unit either by manual control or automatic control, as is illustrated in the embodiment shown in Figures 6 and 7 where the mounting plate 51 is provided with threaded bushings or nuts 71 and 72 in threaded connection with two parallel threaded supporting bars 73, 74, respectively, supported in suitable bearing constructions generally indicated at 75 and 76, respectively, for permitting rotation of the two bars 73, 74 while holding them in parallel relationship and against movement axially; with such an arrangement I provide means for synchronously driving the bars 73, 74 and according to the direction of rotation, the nuts 71, 72 suitably fixed in the carrier plate 51 move lengthwise toward the right or toward the left, as viewed in Figure 6, and carry with them the carrier plate 51 and the applicator structure carried by it.

An illustrative driving means may comprise suitable gearing, such as worm wheels 77 and 78 fixed to the rotatable supporting bars 73, 74 in driving connection respectively with worms 79 and 80 fixed to a driving shaft 81 that extends vertically along the face of the plate-like supporting bracket 13 to which are mounted suitably spaced bearings 82, 83 for rotatably supporting the shaft 81 and for holding it against axial displacement.

Suitable driving means for the shaft 81 are provided and they may take the form of an electric motor 84 (shown on smaller scale in Figure 7) preferably secured to the bracket 13 and provided with a driving connection with shaft 81, preferably by way of a reversible gear drive diagrammatically indicated in Figure 7 at 85 and provided with a suitable control means, such as a handle 86, the shifting of which into either of two positions effects control of the direction of drive of the shaft 81 and hence of the direction of movement of the applicator means.

Motor 84 may be supplied with energy from any suitable source indicated at 87 and, by means, for example, of a switch 88, which may be a push button switch, energization of the motor and hence movement of the mounting plate and applicator element or elements effected, when desired or necessary, to bring another or a new applicator element into action upon the continuously moving element 10, handle 86 of the reverse gear 85 being, of course, initially set to move the multiple applicator unit in the proper direction for that purpose, and being set to reverse the direction of movement when it is desired to restore the carrier plate 51 to its starting point.

Or I may, at the beginning of operations, close the switch 88 to permit the motor 84 to run continuously and in such case I provide suitable means for insuring that the movement of the multiple applicator unit in a direction toward the right, as viewed in Figures 2 and 6, takes place at a sufficiently slow rate so that a new

applicator unit is snapped off of the tubular element 52 or brought into action upon the moving element 10 at suitable time intervals according to the effective life of the applicator element; for example, and depending upon various factors above indicated, the effective life of an active applicator element may be thirty minutes and in such case the rate of drive to effect relative movement between the multiple applicator unit and the tubular element 52 is such that it requires about thirty minutes to effect such movement throughout a distance equal to the equal spacing between successive applicator elements. Thus, with thirteen applicator elements, as shown in Figure 2, they are brought into action upon the moving element 10 successively at the rate of one every thirty minutes and fourteen applicator units would thus suffice for a 6½-hour continuous run.

The achievement of the desired rate at which the applicator units are brought into action is preferably and more conveniently effected by correspondingly controlling the speed of drive of the driving motor 84 itself, having, of course, due regard for the ratio of drive of the gearing between the motor and the bars 73, 74, and illustratively I may provide a suitable speed control illustratively in the form of a rheostat 89 having preferably an "off" position. Thus, by setting rheostat 89, the desired speed of drive may be achieved and switch 88 may be used for starting and stopping or the rheostat 89 with an off position may itself be used also for starting and stopping, and conveniently the speed control device, such as the rheostat 89, is suitably calibrated. For starting a new run, carrier plate 51 is restored to its initial or starting position by shifting the reverse gear control 86 and to effect more rapid movement during this restoring operation, the motor-speed control, such as rheostat 89, is set for maximum motor speed which may be and preferably is sufficiently high to effect restoration in a comparatively short interval of time.

Or, where it is preferable to avoid a wide differential in speed of drive of the motor, or where a step-by-step relative movement between multiple applicator unit and tubular element 22 is preferable, suitable means, such as an arrangement for energizing the motor circuit at suitable intervals, such as every thirty minutes, may be provided, and in Figure 7 such an arrangement is diagrammatically indicated at 90. It may be in effect a time switch and may comprise a rotary circuit closer and interrupter having conductive elements 91 alternated with non-conductive elements 92 which in coaction with a brush 93 hold the circuit of motor 84 open, when the brush contacts a non-conductive element 92 for the desired time interval, such as thirty minutes, and closes the motor circuit, during the time of contact between brush 93 and a conductive element 91, for a sufficient length of time to let the motor effect sufficient relative movement between the above-mentioned parts to bring the next applicator element into action.

With such an arrangement rheostat 89 may be used to set the speed of the motor 84 to accommodate its action to the change in time interval of circuit-closure by the device 90 where the speed of drive of the latter is varied or changed to alter the time intervals between the step-by-step relative movements and a switch 94 may be used to cut the device out at any time and for any desired purpose, including also for the purpose of effecting return of the carrier plate 51 to its initial or starting position. In this latter instance, switch 94

is closed to cut out the device 90, reverse gear control 86 is properly set, and switch 88 held closed for a sufficient time interval to bring the carrier plate 51 to its starting position.

Thus, I may assure continuity of desired coating application without having to interrupt a continuous run of production of element 10. During operation, worn applicator elements of a multiple applicator assembly may be removed from the latter during the operation of the apparatus, such removal taking place after the assemblage has been moved toward the right to bring a new applicator element into action. In such case the endmost applicator element, being the one whose action or operation has become defective or undesirable, may be cut, as by a sharp blade or scissors before or after detaching its flange portion 47^c from the cylindrical portion 47^c of the adjacent element, the connection between these two parts being, as above indicated, preferably a detachable one to facilitate such removal. Such a detachable connection may comprise, for example, a convex rib extending about the flange portion 47^c (Figure 2) of each applicator element and a mating convex groove extending within and about the flange portion 47^c, these parts interfitting and normally resisting separation under normal strains or pulls effected in the general direction of the axis of the unit. In such case disconnection and cutting as above-mentioned are easily effected manually. Or, by way of further example, where parts 47^a and 47^c are cemented together, the cementing is sufficiently strong to stand up under the conditions of operation but yields under applied manual strain to effect such detachment. The line along which severance along a radius may be achieved may also be predetermined, if desired, as by a "tear line" (not shown), suitably formed along a radius of each of the elements for example during molding them where they are made of a material like rubber.

Preferably and more conveniently, however, I may employ an arrangement like that shown in Figure 2 which may comprise a suitably supported plate-like support 95 preferably of a material like fiber or wood and apertured as at 95^a so that moving element 10 passes therethrough. Member 95 movably carries a cutting element like a knife blade 96 preferably detachably mounted in any suitable way in a frame 96^a having sleeve-like end portions 96^b and 96^c slidably mounted on rods 95^b and 95^c, respectively, for movement in a direction to carry the cutting blade 96 with its plane parallel to the moving element 10 and closely adjacent the latter.

Rod members 95^b and 95^c are suitably supported from the support 95, preferably hingedly, as indicated at 95^e and 95^f, whereby, during usual operation of the applicator mechanism, the rods 95^b, 95^c may be swung about the axis of the hinge connections into a position substantially parallel to the plate support 95, thus holding the frame 96^a and the cutting blade 96 away from and out of operative relation to the aperture 95^a and to the moving element 10.

When an applicator element is detached from a preceding one, it may thus be carried by the moving element 10 up against the plate support 95 which halts it, whence the frame 96^a, positioned at the outer ends of the rod members 95^b and 95^c, being preferably biased to such position by springs 95^g and 95^h, may be swung about the axis of the hinge connections into a position alongside of the moving element 10, the detached and halted applicator element thus finding itself

in the space between the left-hand face of the plate support 95 and the cutting edge of blade 86.

Frame 96^a is then moved toward the right, as viewed in Figure 2, and with the detached applicator element backed up by the plate support 95, continued pressure of the cutter blade 86 in a direction toward the right cuts the applicator element along a chord which is parallel to the vertical diameter of the applicator element and sufficiently close to it so that the line of severance is tangent to or intersects the worn aperture of the applicator element. The latter is thus cut into two parts and thus easily removed from the moving element 10. Frame 96^a with cutter 86 may then be swung into an out-of-the-way position, as above noted.

It might be noted that, where the cutting is done by hand, as by the blade or scissors above-mentioned, or torn along a tear line, the line of cutting is preferably along a radius through to the aperture through which the element 12 passes, whence removal from the element 12 follows.

Tubular element 52 is preferably mounted for ease of replacement in any suitable manner. Thus, its left-hand end (Figure 2) may be provided with a sleeve-like member 64 preferably of sheet metal onto which its left-hand end is sleeved and secured, member 64 having a flange 65 to abut against the left-hand face of the bracket 13 for engagement by suitable clamping elements 66 whose clamping action may be effected by screws 67 threaded into the bracket 13. By loosening the screws 67, clamping elements 66, in the form of elongated plate-like members (see Figure 3) may be swung out of overlapping engagement with the flange 65, whence the tubular element 52 may be withdrawn through the hole 14 in the bracket 13 and by reverse operations replaced by a new tubular member 52 whose cross-section may be, it will be understood, different according to the cross-section of the element 10 to be operated upon, the shape of the apertures in the applicator elements 47 being in such case also preferably shaped to correspond.

To guard against failure of a discharge device 34 causing an interruption of the continuous run of production of the element 10 I preferably provide a suitable number of such devices for supplying coating material to the element 10, illustratively four in number, and suitable means for selectively placing them in operative relation to the moving element 10. Thus, referring to Figures 3 and 7, four such discharge chambers or devices 34 are shown and preferably they are mounted in equiangularly spaced relation about the axis of a carrier disk 97 suitably mounted for preferably step-by-step rotary movement at the upper end of the plate-like supporting bracket 13.

Thus, a bolt 98 passing through suitable aligned apertures in the carrier disk 97 and in the bracket 13 secures the former to the latter and furnishes a suitable axis about which the carrier disk 97 may be swung and where the axes of the discharge devices 34 are radial relative to the carrier disk 97, the axis provided by bolt 98 is in a vertical line through the center of the moving element 10 and hence any one of the several discharge devices 34 may be operatively related to the moving element 10 by swinging carrier disk 97 to bring the discharge end of the selected device just above the path of movement of the element 10 and to bring its axis in line with the above-mentioned vertical line.

Preferably, suitable means are provided to insure so fixing the position of any selected discharge device. Such a means may comprise a disk 100 (Figure 1) interposed between the left-hand carrier disk 97 and the left-hand face of bracket 13 to which it is secured as by screws 101, being apertured so as to pass the bolt 98 therethrough and also giving the back face of carrier disk 97 a suitable expanse of flat bearing surface.

Where the carrier disk 97 has four discharge elements 34, it is provided with four equiangularly spaced holes 102 (Figure 3) with which coacts a pin 103 projecting from the face of the interposed disk plate 100, pin 103 being so positioned that when received, upon rotary movement of carrier disk 97, in any one of the four holes 102, a corresponding one of the four supply or discharge devices 34 is accurately positioned in operative relation to the path of movement of the element 10.

Interposed between the nut of the bolt 98 and the bracket 13 is a spring 104 (Figures 1 and 6) against the tension of which carrier disk 97 may be moved with the bolt 98 toward the left by a sufficient amount to disconnect pin 103 and the hole 102 in which it was seated, whence a rotary movement of the desired extent to bring the selected device 34 into the desired position brings a corresponding hole 102 into juxtaposition to the fixed pin 103, whence seating of the pin in the selected hole is permitted by allowing spring 104 again to expand, the snug fit between the hole and the pin 103 definitely fixing the selected discharge device in its operating position. If desired, and as shown in the drawings, there might be as many pins 103 as there are holes 102 and preferably the ends of the pins are rounded over or tapered to facilitate quick setting of the pin or pins into their respective holes.

Thus, should any one discharge device fail or operate defectively it may be quickly shifted out of operative relation to the moving element 10 and another or succeeding one just as quickly brought into operative relation to the moving element, suitable arrangements being made for supplying the latter discharge device with the coating material from the source of supply, as by flexible or disconnectable conduits or piping. For example, and as shown in Figure 3, each pipe-like extension 37 of the various discharge structures 34 may be provided with any suitable quickly releasable means, such as threads 105, to receive the clamping nut 106 rotatably carried by a movably mounted or flexible conduit 107 that leads to the source of supply of coating material and that may thus be quickly disconnected from or connected to a pipe-like extension 37.

The various discharge structures 34 are preferably removably mounted on the carrier disk 97 and are preferably also constructed to permit quick disassembly for replacement of parts or for cleaning, adjustment, or the like. Thus, for example, each device may comprise a relatively heavy main or base portion 108 which may be machined from a casting to provide the pipe-like extension 37, and an upper threaded extension 109 (Figure 2) with which the cap-like closure 40 is in detachable threaded connection, thereby permitting quick removal of the closure 40 and the plunger 38 with its needle point, and to provide an internally threaded part 110 at its lower end (Figure 1) to removably receive a tube-like part 111, the lower end of which is tapered and provided with the above-mentioned discharge

aperture 35, so that removal of the part 111 of the device 34 thus exposes the lower end of the plunger and the needle point.

The part 108 has also a T-shaped extension 113 (Figures 1, 2 and 5) the shank 113a of which is receivable into a radial slot 114 in the carrier disk 97, there being as many slots 114 in the latter as there are to be discharge devices 34, illustratively four. The cross part of each T-shaped extension 113 is transversely slotted, as at 115 (Figures 1 and 5) to snugly receive a holding member which preferably takes the form of a leaf spring 116 one end of which is secured as by a pin 117 to the rear face of the carrier disk 97, there being one such holding device 116 for each slot 114. With the spring member 116 seated in the slot 115, the device 34 is held against movement outwardly from its slot 114. When it is desired, however, to remove a device 34, the spring member 116 is flexed to lift it out of the slot 115 whence the device 34 may be withdrawn from its slot. As is better shown in Figure 1, the above-mentioned disk 100, which carries the pin or pins 103, is interposed between the carrier plate 97 and the bracket 13 and thus also provides appropriate clearance between these two parts to accommodate the cross portions of the T-shaped extensions 113 and the holding members 116.

Thus, disassembly for purposes of cleaning, inspection, conditioning, replacement, or the like, and assembly of the discharge devices individually and with respect to the carrier disk may be quickly achieved.

Also, the apparatus is of wide adaptability and flexibility of control; for example, should it be desired to change the coating material as, for example, when a change in color of applied coating material is desired, shifting of the carrier disk or head 97 may be quickly effected to bring into operative relation to the moving element 10 another discharge device 34 connected to a source of supply of the desired coating material or a coating material of the desired color; such a change may be made during a run or in preparation for a new run.

The effective internal cross-section of the tubular element 52 (Figure 2) may also be proportioned to be adequate to pass therethrough a splice in the element 10 and, depending upon the nature of the splice or like possible protuberance, the expansibility of the applicator device or devices then operating upon the element 10 permits the latter to yield or stretch or pass the protuberance or, as is preferred or may be desired in practice, the operating applicator device or devices may be expanded by sleeving them onto the right-hand end of the member 52, as viewed in Figure 2, and thus remove them from the path of movement of the protuberance, the applicator device or devices being restored to operative relation to the element as soon as the protuberance has passed the point of spreading operation.

Where the expander or tubular element 52 is made of a composite material, as above described, it is preferred to provide its free end with a reinforcing metal ferrule or sleeve 52a whose external end portion and that of the member 52 are preferably tapered off, as indicated in Figure 2, thus to facilitate sleeving the expansible applicator elements onto the element 52, particularly in initially setting up the apparatus whence the parts appear in the general relationship shown in Figure 2.

Thus, it will be seen that there has been pro-

vided in this invention a method and apparatus in which the various objects noted above, together with many thoroughly practical advantages are successfully achieved.

As many possible embodiments may be made of the mechanical features of the above invention and as the art herein described might be varied in various parts, all without departing from the scope of the invention, it is to be understood that all matter hereinabove set forth, or shown in the accompanying drawings is to be interpreted as illustrative and not in a limiting sense.

I claim:

- 15 1. In a method for applying a coating element to a moving elongated element, the steps which comprise moving the elongated element longitudinally at suitable speed, supplying to its external surface the coating material, running the element with the coating material through a plurality of successively arranged applicator devices which have spreader portions for engagement with the moving element to spread the coating material over its surface, holding the spreader portions of the applicator devices out of engagement with the moving element and bringing the spreader portions of the applicator devices successively into operative relation to the moving element at suitable intervals according to the change in action of an operating spreader portion of a device caused by its continued action upon the moving element.
- 20 2. In a method for applying a coating element to a moving elongated element, the steps which comprise supplying to a heated moving elongated element a coating material settable in response to heating, running the element with the coating material thereon into operative relation to a plurality of applicator devices having spreader portions for spreading the coating material relative to the surface of the elements, and bringing the spreader portions of said devices successively into action upon the moving element at suitable intervals.
- 25 3. In a method for applying a coating element to a moving elongated element, the steps which comprise supplying to a heated moving elongated element a coating material settable in response to heating, running the element with the coating material thereon into operative relation to a plurality of applicator devices having spreader portions made of a pliant material for spreading the coating material relative to the surface of the element, and bringing the spreader portions of said devices successively into action upon the heated moving element at suitable intervals according as the action of an operating spreader portion is altered by change in the characteristics of said pliant material.
- 30 4. In a method for applying a coating element to a moving elongated element, the steps which comprise moving the elongated element in the direction of its length through a plurality of successively arranged applicator devices each of which has an elastic apertured spreader portion which in operation is constricted about and against the surface of said moving elongated element to effect spreading of the coating material, holding the elastic spreader portions of certain of said applicator devices in expanded or distended form to hold them out of action upon the moving element and releasing a distended spreader portion to bring it into action upon the coating material and moving element.
- 35 5. In a method for applying a coating element

to a moving elongated element, the steps which comprise running the elongated element with coating material supplied thereto through the aligned apertures of a plurality of rubber spreader members of which all but that one or those needed to effect spreading of the coating material are held distended and out of action upon the element, and releasing such of the distended spreader members into action upon the moving element and at such time intervals as determined by departure from intended spreading action of that member or those members active upon the moving element.

6. In a method for applying a coating element to a moving elongated element, the steps which comprise running the elongated element through a tube-like expander having strung thereover and expanded thereby a plurality of contractible applicator elements which are by said expander held out of operative relation to the moving element, and effecting relative movement between said expander and said applicator element expanded thereby, as to disengage one from the other and permit the applicator element to contract and become operative upon the moving element.

7. In a method for applying a coating element to a moving elongated element, the steps which comprise sleeving onto a tube-like expander all but the endmost one of a plurality of successively arranged contractible applicator elements, running the elongated element through said expander and through said endmost applicator element whereby the latter effects spreading of a coating material onto the surface of the moving elongated element and said expander holds expanded, and out of action upon said elongated member, the rest of said applicator elements, and effecting relative movement between said expander and applicator elements expanded thereby to bring the latter successively and at suitable intervals into action upon the moving elongated element.

8. An apparatus for applying a coating material to a moving elongated element comprising a plurality of successively arranged applicator devices which have spreader portions adapted for engagement with the moving element to spread the coating material over its surface, means for supplying to the moving element coating material to be spread over its surface, means for holding the spreader portions of said applicator devices out of engagement with the moving element, and means for releasing the spreader portions of said applicator devices successively and at suitable intervals to bring spreader portions into operative relation to the moving element substantially in accordance with the change in action of an operating spreader portion caused by its continued action upon the moving element.

9. An apparatus as claimed in claim 8 in which the spreader portions comprise respectively elastic apertured members with their apertures aligned along the line of movement of said elongated element and any one of which, when in operation upon the elongated element is constricted about and against the surface of the latter to effect spreading of the coating material, and said holding means comprises means holding the elastic apertured members in expanded or distended form.

10. An apparatus for applying a coating material to a moving elongated element comprising a plurality of rubber spreader members each having an aperture proportioned to the cross-section

of the elongated element to effect spreading of coating material about the surface of the moving element, means supporting said spreader members with their apertures aligned along the line of movement of said elongated element, means for holding such of the spreader members as are not operating upon the moving element in distended form and hence out of action upon the element, and means for effecting release of distended spreader members as desired.

11. An apparatus for applying a coating material to a moving elongated element comprising a tube-like expander through which the elongated element moves and having strung thereover and expanded thereby a plurality of contractible applicator elements which are by said expander held out of operative relation to the moving element, and means supporting said plurality of applicator elements and said tube-like expander for relative movement therebetween in the general direction of the length of said expander, thereby to permit successive release of contractible applicator elements from an end of said expander to contract and become operative upon the moving element.

12. An apparatus as claimed in claim 11 in which there is means mounting that end of said tube-like expander adjacent to which an applicator element is operative upon the moving element for movement in directions transverse to the line of movement of said elongated member, thereby to follow transverse sway or movement of said elongated member.

13. An apparatus as claimed in claim 11 in which said tube-like expander element is pliant and said supporting means therefor engages the end thereof remote from the end adjacent to which an applicator element is operative upon said moving element, whereby said last-mentioned end with an operating applicator element may partake of movement in directions transverse to the general line of movement of said elongated member in response to vibration or sidesway of the latter.

14. An apparatus for applying a coating material to a moving elongated element comprising a tube-like expander through which the elongated element moves and having strung thereover and expanded thereby a plurality of contractible applicator elements which are by said expander held out of operative relation to the moving element.

15. An apparatus for applying a coating material to a moving elongated element comprising a tube-like expander through which the elongated element moves and having strung thereover and expanded thereby a plurality of contractible applicator elements which are by said expander held out of operative relation to the moving element, means holding said applicator elements together and in spaced relation, and means mounting said expander and said holding means for relative movement in the direction of the length of said expander, whereby upon relative movement therebetween to effect disengagement between an applicator element and said expander, a disengaged applicator element contracts about and becomes operative upon the moving elongated element.

16. An apparatus as claimed in claim 15 in which said mounting means has coating with it spaced stop means for permitting said relative movement to take place in a succession of steps, one for each applicator element.

17. An apparatus as claimed in claim 15 having

ing means for effecting substantially continuous relative movement between said applicator elements and said expander at a rate commensurate with the rate at which it is desired to bring said applicator elements successively into operation upon the moving element.

18. An apparatus as claimed in claim 15 having motive means for effecting said relative movement, and means for controlling the direction in which said relative movement takes place.

19. An apparatus as claimed in claim 15 having motive means capable of effecting relative movement between said applicator elements and said expander, and means for effecting actuation of said motive means at suitable intervals to effect substantially step by step relative movement to bring said applicator elements into operation successively.

20. An apparatus as claimed in claim 15 in which said means for holding said applicator elements together and in spaced relation comprises also means providing for detachment of individual applicator elements, whereby an applicator element may be removed out of operative relation to the moving element and said expander.

21. An apparatus as claimed in claim 15 in which said means for holding said applicator elements together and in spaced relation comprises also means providing for detachment of individual applicator elements, there being means whereby an applicator element may be parted to permit its removal from said moving element.

22. An apparatus as claimed in claim 15 in which said means for holding said applicator elements together and in spaced relation comprises also means providing for detachment of individual applicator elements, said applicator elements having a weakened portion forming a tear line along which each applicator element may be parted for removal from about said moving element.

23. An apparatus as claimed in claim 15 in which said means for holding said applicator elements together and in spaced relation comprises also means providing for detachment of individual applicator elements, and severing means operable to sever an applicator element thereby to permit cutting of the applicator element for removal from about the moving element.

24. An apparatus for applying a coating material to a moving elongated element comprising spreader means operating upon said element at one point in its path of movement for distrib-

uting coating material, a plurality of discharge devices each having means forming part of a detachable connection with a means forming a source of supply of coating material, and means movably mounting said plurality of discharge devices for selectively positioning them to discharge coating material onto said moving element in advance of said point.

25. An apparatus for applying a coating material to a moving elongated element comprising spreader means operating upon said element at one point in its path of movement for distributing coating material, a plurality of discharge devices each capable of emitting coating material onto said moving element at a rate commensurate with the speed of movement of the latter and the surface area thereof to be covered by coating material, and means movably mounting said plurality of discharge devices for selectively positioning them to discharge coating material onto said elongated element at a point in its path of movement in advance of said first-mentioned point.

26. An apparatus for applying a coating material to a moving elongated element comprising spreader means operating upon said element at one point in its path of movement for distributing coating material, a plurality of means each capable of applying coating material to said moving element in advance of said point, and means for selectively bringing said plurality of means and the moving elongated element into operative relation to each other.

27. An apparatus for applying a coating material to a moving elongated element comprising a hollow member through which the elongated element freely passes, said hollow element being constructed and mounted for yieldable displacement in directions transversely of the line of movement of said elongated element, means for supplying to the moving element coating material to be spread over its surface, and an applicator device having spreader means in operative relation to the moving element to spread coating material over its surface and having means supporting it from said yieldable supporting element whereby said spreader means may partake of bodily movement in directions transverse of the line of movement of said moving element to accommodate itself to corresponding transverse movements of the moving element.

CHARLES W. ABBOTT.
